Attorney, Agent, or Firm—Cumpston & Shaw

[57] **CLAIM**

The ornamental design for a high chair, substantially as shown and described.

DESCRIPTION

FIG. 1 is a perspective view of the front, top and left sides of a high chair showing my new design; FIG. 2 is a rear elevational view thereof; and FIG. 3 is a right-side elevational view thereof, the left side being substantially a mirror image thereof.

FIG. 1

FIG. 2
